Charles Smith, 7700 S. Wabash Ave.,
Chicago, Ill. 60619

Filed Apr. 29, 1966, Ser. No. 2,072

Term of patent 14 years

(Cl. D56—1)

FIG. 1 is a front elevational view of a guitar or the like embodying my new design;

FIG. 2 is a side elevational view thereof;

FIG. 3 is an end elevational view looking toward the left from the plane of line 3—3 in FIG. 2; and

FIG. 4 is an end elevational view looking toward the right from the left end in FIG. 2.

The back is substantially plain.

The dominant features of my design reside in the portions shown in full lines.

I claim:

The ornamental design for a guitar or the like, substantially as shown and described.
